(57) **CLAIM**

The ornamental design for a shoe sole as shown and described.

DESCRIPTION

FIG. 1 is a bottom view of a shoe sole in a first configuration showing our new design;

FIG. 2 is a top view thereof;

FIG. 3 is a front view thereof;

FIG. 4 is a rear view thereof;

FIG. 5 is a left side view thereof;

FIG. 6 is a right side view thereof;

FIG. 7 is a perspective view thereof;

FIG. 8 is an enlarged view of portion 8 shown in FIG. 7;

FIG. 9 is an enlarged view of portion 9 shown in FIG. 7;

FIG. 10 is a bottom view of a shoe sole in a second configuration showing the spike claws in retracted position;

FIG. 11 is a top view thereof;

FIG. 12 is a front view thereof;

FIG. 13 is a rear view thereof;

FIG. 14 is a left side view thereof;

FIG. 15 is a right side view thereof;

FIG. 16 is a perspective view thereof;

FIG. 17 is an enlarged view of portion 17 shown in FIG. 16;

FIG. 18 is an enlarged view of portion 18 shown in FIG. 16;

FIG. 19 is a perspective view of the shoe sole showing the switching state of the spike part;

FIG. 20 is an enlarged view of portion 20 shown in FIG. 19; and,

FIG. 21 is an enlarged view of portion 21 shown in FIG. 19.

(Continued)

The dot-dot-dash broken lines represent boundaries of the enlarged portions and form no part of the claimed design.

1 Claim, 21 Drawing Sheets
